SHEET ROLLING DEVICE

Edward C. Wells, Skokie, and Richard C. Robertson, Mount Prospect, Ill., assignors to Charles Bruning Company, Inc., Mount Prospect, Ill., a corporation of Delaware

Filed June 7, 1960, Ser. No. 34,443
10 Claims. (Cl. 242—65)

This invention relates to a sheet rolling device and more particularly to a device for rolling up tracings which have passed through a printing or duplicating machine.

It is conventional to store sheet material such as tracings, for example, either flat, or in roll form, with the face of the sheet provided with a set curl referred to in the art as a face-in curl, which in this specification will be hereinafter referred to as a face curl, or with the back of the tracing provided with a set curl, commonly termed a back-in curl, hereinafter referred to as a back curl. After feeding such tracings through a printing, duplicating, or other machine in flat form, it is often desirable, at least in the case of previously rolled tracings, to re-roll the same for storage in accordance with their initial curl. Alternatively, the tracings, after duplication thereof, may desirably be fed flat to a receiving tray for stacking and storage.

It is an object of this invention to provide a sheet rolling device for rolling up sheet material such as tracings passing out of printing, duplicating, or other machines so that the sheet material is rolled up in accordance with its original curl, thus minimizing wear and distortion of the sheet material, in that it is not subjected to forces introducing additional curling stresses.

A further object of the invention is the provision of such a device which is adapted to deliver tracings flat or to roll them up with either a face or back curl.

Other objects and advantages of the invention will be apparent from the following detailed description thereof.

The sheet rolling device of this invention comprises, a feed means for advancing the sheets, a plurality of movable guide fingers for guiding the advancing sheets positionable to guide the moving sheets to produce a face curl or back curl or to one or more idle positions where they have no guiding function and the sheets are fed substantially flat, and a feed roller, rotatable in opposite directions, for rolling the sheets with face or back curls as desired, depending upon the position of the guide fingers and the direction of rotation of the feed roller.

In the accompanying drawings forming a part of this specification and showing, for purposes of exemplification, a preferred form of this invention without limiting the claimed invention to such illustrative embodiment:

FIGURE 1 is a vertical cross-section through a portion of a duplicating machine, showing a sheet rolling device according to this invention, with the guide fingers positioned for rolling up sheet material such as tracings having face curls to re-roll them with such curls;

FIGURE 1a is a fragmentary cross-section of the sheet rolling device of FIGURE 1, showing the guide fingers in position for rolling up tracings, having back curls to re-roll them with such curls;

FIGURE 1b is a view similar to FIGURE 1a with the guide fingers in their idle position for feeding the tracings in flat form;

FIGURE 2 is a front elevation, partly in section, of the sheet rolling device taken along the line 2—2 of FIGURE 1;

FIGURE 3 is a plan view of the lower assembly of the sheet rolling device, taken along the line 3—3 of FIGURE 1b;

FIGURE 4 is a vertical section through the lower as-

2

sembly of the sheet rolling device, with the lower guide fingers in the idle position; and

FIGURE 5 is a vertical section similar to FIGURE 4 with the lower guide fingers elevated to the face or back curl position.

Referring first to FIGURE 1, a portion of a known duplicating machine is shown, comprising a light transmitting printing cylinder 10, within which is located a lamp 11 and a ventilating duct 12. As conventional, the printing cylinder is mounted for rotation about its axis. Endless carrier bands or tapes 13 pass thereover, along with auxiliary feed belts 14 from adjacent a feed board 15 to the printing cylinder 10. The superposed feed belts and endless bands form a traveling platform for receiving sheets, such as tracings 16, and sensitized copy papers 17, and for conveying the assembly comprising the superimposed tracings and copy papers to the printing cylinder 10. The tracings and copy papers are passed around the light transmitting portion of the printing cylinder by the endless bands or tapes 13 and the sensitized copy papers 17 are there exposed through the tracings 16. The endless band conveys the exposed sheets past a sheet separating device, indicated generally at 18, which may be of any well known structure, such as that disclosed in Streich, U.S. Patent 2,441,912, granted May 18, 1948, for example. The copy papers 17, separated from the tracings 16, pass upwardly with the endless bands 13, over a roller 19 and then to a conventional developing device, not shown, or to the delivery point, if development is unnecessary. The separated tracings 16 pass through the sheet rolling device of the present invention, indicated generally by reference numeral 20, to be described in more detail hereinafter, in which the tracings are rolled in accordance with their original curl, i.e., with either a face or back curl, as the case may be, or are fed flat, as desired. The tracings, when fed flat, pass over rollers 21 to a receiving tray 22, as shown in FIGURE 1b.

The sheet rolling device is a self-contained unit suitable for use wherever desired. As shown in FIGURES 1 and 2, the embodiment utilized with the duplicating machine of FIGURE 1, includes a hinged feed shelf 23 over which the tracings 16 are fed by a pair of feed rollers consisting of a feed roller 24 having spaced feed rings 25, desirably of rubber, and a cooperating feed roller 26 having spaced discs 27 mounted thereon. The discs 27 are preferably formed of a smooth high friction material, such as rubber, for example, and have in their periphery a series of peripheral notches 28 for corrugating or ribbing the tracings to facilitate feeding to the receiving tray 22, when the guiding fingers of the sheet rolling device are in the idle positions, as will be more fully described hereinafter.

The cooperating feed roller 26, best shown in FIGURE 2, is mounted for rotation about a shaft 29 in bearings 30 at the ends of the shaft 29. Each of these bearings 30 is mounted in a bearing support or spacer 31 which is fixed to the shaft 29 for rotation therewith by a set screw 31a. A number of the discs 27 (six are shown by way of illustration in FIGURE 2) are spaced along the length of the cooperating feed roller 26 by spacers 32 and are held in place by rings 33, desirably of metal, the latter being of smaller diameter than the discs 27 and disposed on opposite sides thereof. Additionally, a pair of drive wheels 34 of a tough, abrasion-resistant material, such as nylon, for example, are mounted on the bearing spacers 31 at the ends of the cooperating roller 26 and fixed thereto by set screws 34a.

The feed roller 24 is driven from a motor, either directly or through a conventional belt or chain drive. Feed roller 24, in turn, drives the cooperating feed roller 26 through drive wheels 35, raised portions 35a of the drive

wheels driving the cooperating roller when rolling the tracings, and lowered portions 35b driving the cooperating roller when feeding the tracings in substantially flat condition.

Slightly above and to the left of the cooperating feed roller 26, viewing FIGURE 1, is a mounting tube 36 supporting a number of upper guide fingers 37. Each upper guide finger, which is suitably secured to the mounting tube 36 as by a set screw 38, is pivotally linked to a finger extension 39 by a screw 40 having a finger spacer 41 thereon. The finger extension is arcuate shaped and includes a convex surface 39a and a concave surface 39b, for guiding tracings fed into the rolling device, as will appear hereinafter. While three upper guide fingers and finger extensions are shown in the drawings, it will be understood that any number may be employed, depending upon the width of the pathway through the sheet rolling device and the widths of the tracings to be passed therethrough.

The mounting tube 36 (FIGURE 2) is mounted for pivotal movement on an upper finger shaft 42. Pivotal movement of the mounting tube about shaft 42 is effected by either of a pair of knurled collars 43 attached to the mounting tube 36 by set screws 44. Each end of the shaft 42 is attached to a pivoted arm 45 by a head screw 46. Immediately adjacent the right pivoted arm 45, as viewed in FIGURE 2, a setting block 47 is fixed to the mounting tube 36 by a set screw 48. The setting block 47 includes a spring loaded ball plunger 49 locking in an aperture 50 in the right pivoted arm 45. Several such apertures are provided in the right pivoted arm radially of the support for the upper finger shaft 42 and the mounting tube 36. Thus, the mounting tube 36, upon pivotal movement effected by turning either of the knurled collars 43, is locked in any of a number of predetermined positions by the ball plunger 49 engaging one of the apertures 50 in the right pivoted arm 45. The locations of the apertures in the right pivoted arm 45 are such as to position the upper guide fingers 37 and finger extensions 39, which fingers 37 are attached to the mounting tube 36, in the face curl, back curl, and idle positions thereof, as shown in FIGURES 1, 1a and 1b, respectively.

The shaft 29 is joined to the pivoted arm 45 by head screws 51. The shaft 29 and the upper finger shaft 42, together with the elements thereon, comprise a unitary upper assembly 52. As may be seen in FIGURES 1, 1a, 1b and 2, the upper assembly 52 is positioned contiguous to and above the feed roller 24.

The upper assembly 52 is pivotally mounted on the side walls of the duplicating machine by a pair of pivot pins 53 (see FIGURE 1) extending between the side walls of the duplicating machine and the adjoining pivoted arms 45. Each of the pivot pins 53 has one end fixed to the pivoted arms 45 and the other end mounted in a slot in the frame of the machine to permit movement of the upper assembly relative to the frame of the duplicating machine.

The upper assembly 52 is mounted so that it can be moved to one of two positions. In one position, which will hereinafter be termed the upper position, for rolling tracings passed between the feed rollers 24 and 26, the peripheral edges of the feed rings 25 on the feed roller 24 and the peripheral edges of the discs 27 on the cooperating feed roller 26 extend only to the plane of the tracing 16 (as shown in FIGURE 2). In this upper position, the raised portions 35a of the drive wheels 35 on the feed roller 24 are in driving engagement with the drive wheels 34 of the cooperating feed roller 26.

In the second or lower position of the upper assembly 52, which facilitates feeding the tracings in substantially flat form through the device, the peripheral edges of the feed rings 25 on the feed roller 24 extend slightly above the peripheral edges of the discs 27 on the cooperating feed roller 26. In such lower position, the feed rings

25 and discs 27 slightly corrugate or rib the tracing to facilitate feeding and delivery to the receiving tray 22, where the tracings are stacked in substantially flat form. When the upper assembly 52 is in the lower position, the smaller diameter portions 35b of the drive wheels 35 on the feed roller 24 engage and drive the drive wheels 34 of the cooperating feed roller 26.

Desirably, the upper assembly is mounted for ready positioning into the upper and lower positions described above, by a bracket 54 secured by screws 55 to a side wall section 56 of the duplicating machine adjacent to and below the left pivoted arm 45. A bracket extension 57, at right angles to the bracket 54, is provided with a raised portion or shelf 57a and a ledge 57b. As shown in FIGURE 2, when the drive wheels 34 on the cooperating feed roller 26 engage the raised portions 35a of the drive wheels 35 on the feed roller 24 (viz. the upper position of the upper assembly 52), the left pivoted arm 45 rests on the raised portion 57a of the bracket extension 57. In the lower assembly position described, i.e., when the drive wheels 34 engage the smaller diameter portions 35b of the drive wheels 35, the left pivoted arm 45 rests on the ledge 57b of the bracket extension 57.

A pair of handles or knobs 58, mounted on the pivoted arms 45 by screws 59 having spacers 60 thereon, are utilized to move the upper assembly 52 from one to the other of the two positions described above. The handles 58 effect pivoting of the upper assembly about the pivot pins 53 to pivot the left pivoted arm 45 thus moving the lower edge thereof above the raised portion 57a of the bracket extension 57 and also moving the drive wheels 34 above the raised portions 35a of the drive wheels 35. The handles then are utilized to effect sidewise displacement of the upper assembly. The upper assembly 52, if in the upper position, shown in FIGURE 2, can thus be moved to the lower position with arm 45 resting on ledge 57b, in which position the shoulder at right angles to ledge 57b prevents lateral movement to the right, viewing FIGURE 2 of the upper assembly. The assembly is moved in reverse direction in substantially the same manner.

The sheet rolling device includes a lower assembly 61 assisting in feeding the trackings 16. The lower assembly comprises a supporting housing 62 (FIGURES 4 and 5) having a rear tray section 63, a mounting section 64 and a front tray section 65. The lower assembly 61 is positioned contiguous to and below the feed roller 24.

The rear tray section 63 is provided along its upper edge with a number of upstanding portions 66 separated by slots 67 (FIGURES 2 and 3), through which slots the feed rings 25 on the feed roller 24 rotate. The upstanding portions 66 of the rear tray section prevent the tracings 16 from being carried behind the feed roller by the feed rings 25. At the ends of the rear tray section, a pair of brackets 68 having cut-outs 69 are provided for attaching the lower assembly to the side walls of the duplicating machine as, for example, by hexagonal head screws 70, as shown in FIGURES 4 and 5.

A cover plate 71 having a number of slots 72 spaced along the length thereof is mounted on the mounting section 64 of the supporting housing with the aid of brackets 73 and screws 74 (see FIGURES 3 and 5). The cover plate is so positioned as to prevent snagging the leading edges of the trackings 16 on the lower finger shaft described hereinafter.

The front tray section 65 of the supporting housing has a number of T-shaped slots 75 positioned along its length; the leg portion of each of the slots is aligned with one of the corresponding slots 72 in the cover plate 71 (see FIGURE 3). The front tray section is provided additionally with a pair of aligning knobs 76 (FIGURES 1 and 3) spaced along the length of the section for guiding the tracings 16 as they are fed out of the sheet rolling device.

A lower finger shaft 77 is mounted for pivotal movement within the supporting housing 62; the shaft is journaled at its ends in sockets 78 which are, in turn, attached to brackets 70; the brackets are held fixed relative to the supporting housing by screws 80. As shown in FIGURES 2 and 3, sidewise displacement of the lower finger shaft is prevented by the provision of a collar 82 immediately adjacent the socket 78.

A number of lower guide fingers 83 are attached to the lower finger shaft 77 at spaced points by mounting collars 84 secured thereto by set screws 85. Each of the lower guide fingers has an upper planar surface 86 and a lower concave arcuate guiding surface 87, the latter surface designed to guide the tracings 16 during rolling thereof. The lower guide fingers are each aligned with one of the lateral slots 72 in the cover plate 71 and with the corresponding leg elements of each of the T-shaped slots 75 in the front tray section 65. The fingers are thus pivotable through an arc extending through and above the plane of the cover plate. It will be noted that, like the upper guide fingers 37, any number of the lower guide fingers 83 may be employed as desired, depending upon the width of the pathway through the sheet rolling device and the widths of the tracings to be passed therethrough.

Adjustment of the lower finger shaft 77, together with the attached lower guide fingers 83, is effected by a knurled collar 88 mounted on the finger shaft with a set screw 89 and housed within an opening 90 in the cover plate 71. The pivotal movement of the finger shaft is restricted by a pair of stop collars 91 and 92 and the brackets 93 and 94 associated therewith supported on the mounting section 64.

As seen in FIGURES 3 and 4, the stop collar 92 has a dowel pin 95 which turns as the lower finger shaft is turned by the knurled collar 88. The pivotal movement of the shaft is limited in one direction by engagement of the dowel pin 95 with an inwardly extending flange 96 of the bracket 94. When the dowel pin 95 engages the flange 96 the upper planar surface 86 of each of the lower guide fingers 83 is positioned in the plane determined by the cover plate 71 and the front tray section 65. It is important that the rear surfaces of the cover plate and the front tray section be coplanar and in alignment with one another, and that the upper surfaces of the lower guide fingers 83 be pivotable into the plane of these surfaces, and yet not rotate further than this limiting position, so that the lower guide fingers when so positioned serve to guide the tracings for delivery to the receiving tray 22 in substantially flat form without snagging the leading edges of the tracings. The aforesaid limiting position is an idle position with respect to the rolling or curling of the tracings 16, i.e., as shown in FIGURE 4, with the lower guide fingers in the plane of the cover plate and the front tray section, the tracings 16 are not curled but are rather fed to the receiving tray in sheet form for stacking.

The stop collar 91 having a dowel pin 97 therein, as shown in FIGURES 3 and 5, limits the movement of the lower finger shaft 77 by engaging an inwardly directed flanged 98 of the bracket 93. When the dowel pin 97 engages flange 98, the lower guide fingers 83 fixed to the lower finger shaft, are positioned, as shown in FIGURE 5. In this position of the lower guide fingers, frictional contact thereof with the feed roller 24 does not take place, and the arcuate guiding surfaces 87 of the lower guide fingers are positioned for re-forming face or back curls on the tracing 16, as discussed hereinafter.

A lower feed roller 99 is journaled on ball bearings 100 which are mounted in ball bearing housings 101. The ball bearing housings are, in turn, mounted on the brackets 79 secured to the supporting housing 62. The lower feed roller is driven by a drive wheel 102, desirably having rubber peripheral surfaces, which is frictionally driven. The drive wheel 102 is driven from any

suitable drive, such as a motor drive arranged to optionally drive the lower feed roller in opposite directions and to disengage same from the motor drive at will, using conventional switch means. Since such drives and switch mechanisms are well known in the art, it is believed unnecessary to further describe them.

A number of discs 103, desirably of rubber, are located in pairs at spaced distances along the length of the lower feed roller 99. Each pair of discs is positioned 10 in alignment with one of the T-shaped slots 75 of the front tray section 65 of the supporting housing 62, as shown in FIGURE 3. The members of each pair of discs are spaced apart on opposed sides of the plane of the lower guide fingers 83 which, as described above, are 15 aligned with the leg elements of the T-shaped slots. The discs 103 serve to feed the tracing 16 through the sheet rolling device and aid in the re-rolling with face curls and back curls, as desired.

In the operation of the sheet rolling device of the invention, a tracing 16 and copy paper 17 are fed through 20 the duplicating machine and are separated after printing by the sheet separating device 18. Thereafter, the separated tracing is fed over the feed shelf 23 and between the feed roller 24 and the cooperating feed roller 26.

25 In order to re-roll a tracing originally having a face curl, the handles 58 are actuated to pivot the upper assembly 52 about the pivot pins 53; the upper assembly is then displaced (into its upper position) so that the drive wheels 34 engage the raised portions 35a of the drive 30 wheels 35 (see FIGURE 2) and the peripheries of the feed rings 25 and discs 27 extend to the plane of the tracing. Either of the knurled collars 43 is then turned and snapped in place by the ball plunger 49 seating in the aperture 50, with the upper guide fingers 37 and the 35 finger extensions 39 pivoted into the position shown in FIGURE 1. The lower guide fingers are then pivoted into the elevated position of FIGURE 1 by movement of the knurled collar 88. The conventional motor drives for the feed roller 24 and the lower feed roller 99 are 40 then engaged; in order to re-form a face curl, the feed roller 24 is rotated counter-clockwise while the lower feed roller 99 is rotated clockwise. Of course, it will be understood that each of the feed rollers may be engaged by a common drive mechanism, provided suitable gearing for varying the rates and directions of rotation is provided.

45 The tracing is fed between the feed roller 24 and the cooperating feed roller 26 and is guided by the slightly downward curvature of the concave surfaces 39b of the finger extensions 39 into a counter-clockwise or face curl. 50 The rotating discs 103 on the lower feed roller 99 drive the tracing into contact with the elevated concave guiding surfaces 87 of the lower guide fingers 83 and feed the tracing into a continuous roll. As the tracing is 55 rolled, it will be noted the finger extensions 39 of the upper guide fingers 37 pivot slightly outward of the roll to account for the increased size thereof. The formed roll is thereafter removed manually.

To re-roll tracings originally having a back curl, the 60 upper assembly 52 and the lower guide fingers 83 are positioned as described above in connection with the re-forming of a face curl. Either of the knurled collars 43 is then snapped into the position corresponding to the position of the upper guide fingers and finger extensions 39, 65 shown in FIGURE 1a. The drives for the feed roller 24 and the lower feed roller 99 are then actuated, with each of the rollers rotating counter-clockwise, and the tracing is fed between the feed roller 24 and the cooperating feed roller 26, and is guided by the almost vertically 70 disposed finger extension 39 into a clockwise or back curl. The concave guiding surfaces 87 of the lower guide fingers 83 guide the tracing in a clockwise direction and the rotating discs 103 on the lower feed roller feed the tracing into a roll, which is removed thereafter.

75 In order to feed the tracings in substantially flat form

through the device, as shown in FIGURE 1b, the upper guide fingers 37 are pivoted into an idle position above the cooperating feed roller 26, and the lower guide fingers are pivoted into an idle position with the upper surfaces 86 of the guide fingers in the plane of the cover plate 71 and the front tray section 65. As indicated above, the upper and lower guide fingers are pivoted by the manual actuation of the knurled collars 43 and 88, respectively. Upon actuating the feed roller 24 (the lower feed roller 99 may be disengaged), the tracings 16 are feed through the sheet rolling device to the receiving tray 22.

Desirably, when fed in sheet form, the tracings are slightly ribbed or corrugated to facilitate feeding to the receiving tray 22 of the duplicating machine whereat they are stacked in substantially flat form. Corrugating or ribbing is effected by raising the handles 58 of the upper assembly 52 of the sheet rolling device, and longitudinally displacing the upper assembly to its lower position in order that the feed rings 25 on the feed roller 24 and the discs 27 on the cooperating feed roller 26 intermesh. When thus intermeshed, the tracings fed between the discs and the feed rings are ribbed as desired.

It will be noted that the present invention provides a sheet rolling device for rolling up sheet material with face or back curls or for delivering same substantially flat, according to the initial configuration of the sheet material, which is simple, convenient and efficient.

Since different embodiments of the invention may be made without departing from the scope thereof, it is intended that all matter contained in the above description or shown in the accompanying drawings shall be interpreted as illustrative and not in a limiting sense.

What is claimed is:

1. A sheet rolling device for rolling a sheet having a face curl to produce a roll in which the sheet has a face curl and for rolling a sheet having a back curl to produce a roll in which the sheet has a back curl, comprising, in combination, a guiding surface defining one side of a substantially unobstructed sheet rolling zone, a plurality of guide fingers having guiding surfaces positioned in said sheet rolling zone opposite the first mentioned guiding surface, feed means for advancing a sheet into said sheet rolling zone between the guiding surfaces on said fingers and said first mentioned guiding surface, said guiding fingers being positionable in said rolling zone in one position for guiding said sheet to roll it up with a face curl and in a second position for guiding said sheet to roll it up with a back curl, a feed roller having its periphery disposed adjacent the base portion of said rolling zone for frictionally engaging and rolling up the sheet in one direction for forming a roll with the rolled-up sheet having a face curl and being rotatable in the opposite direction for forming a roll with the rolled-up sheet having a back curl.

2. The device as defined in claim 1, in which said guide fingers comprise a group of upper fingers and a group of lower fingers and including a supporting means for each group of fingers on which each said group is mounted for pivotal movement.

3. The device as defined in claim 2, in which the supporting means for said group of upper fingers is mounted for pivotal movement to position said upper fingers in a first position for guiding said sheet to roll it up with a face curl, in a second position for guiding said sheet to roll it up with a back curl, and in a third idle position allowing delivery of said sheet in substantially flat form, and the supporting means for said group of lower fingers is mounted for pivotal movement to position said lower fingers in a first position for guiding said sheet to roll it up with a face or back curl and in a second position for guiding said sheet for delivery in substantially flat form.

4. A sheet rolling device for sheets, which have passed through a duplicating machine, to roll up said sheets with a face curl in the rolled sheet, with a back curl in the rolled sheet, or to deliver said sheets substantially flat,

comprising in combination, an upper feed means for advancing said sheets endwise in one direction, a plurality of spaced apart upper guide fingers disposed adjacent said upper feed means, a mounting element to which each of said upper guide fingers is connected, a plurality of finger extensions each of which is pivotably connected to one of the upper guide fingers at the end of the guide finger remote from said mounting element, said mounting element being pivotable through at least three predetermined positions corresponding to the positions of said upper guide fingers and finger extensions for guiding said sheets for rolling with face curls or back curls on said sheets or for feeding same in flat form, locking means provided on said mounting element for holding said mounting element in said predetermined positions, a plurality of spaced apart lower guide fingers each having a concave guiding surface for said sheets, a pivotable supporting means to which said lower guide fingers are connected, limit means on said supporting means for limiting the pivotal movement thereof, and a feed roller adjacent said pivotable supporting means cooperating with said upper and lower guide fingers for rolling said sheets fed by said feed means between said fingers, said feed roller being rotatable in opposite directions for rolling said sheets with face or back curls thereon.

5. The sheet rolling device of claim 4 in which said upper feed means includes an upper feed roller and a cooperating feed roller driven thereby, said upper and cooperating feed rollers each having a plurality of spaced annular sheet engaging members thereon which are laterally offset from one another and are adapted to feed said sheets as they are advanced therebetween or to intermesh with one another for corrugating said sheets.

6. A sheet rolling device for sheets which have passed through a duplicating machine, for rolling sheets having face curls to provide rolls in which the sheets have face curls, for rolling sheets having back curls to provide rolls in which the sheets have back curls, and for delivering uncurled sheets substantially flat, comprising, in combination, an upper assembly, an upper feed roller associated with said upper assembly, and a lower assembly; said upper assembly comprising a rotatably mounted cooperating feed roller engaged and driven by said upper feed roller, a pivotably mounted upper supporting member, a plurality of spaced apart upper guide fingers fixedly mounted at their ends on said upper supporting member, and a plurality of arcuate shaped finger extensions, each of which is pivotably connected to one of the upper guide fingers at the end of the guide finger remote from said upper supporting member, said upper guide fingers positionable in one position for guiding said sheets to roll them up with a face curl and positionable in another position for guiding said sheets to roll them up with a back curl; and said lower assembly comprising a rotatably mounted lower feed roller, a pivotably mounted lower supporting member and a plurality of spaced apart lower guide fingers fixedly mounted on said lower supporting member having concave guiding surfaces arranged to be positioned adjacent said feed roller for guiding said sheets, said lower feed roller being rotatable in one direction for forming a roll with the rolled-up sheet having a face curl and being rotatable in the opposite direction for forming a roll with the rolled-up sheet having a back curl.

7. The sheet rolling device defined in claim 6, in which said upper assembly is laterally and longitudinally displaceable with respect to said upper feed roller and both said upper feed roller and said cooperating feed roller have spaced apart series of discs thereon adapted to intermesh with one another for slightly corrugating the sheets fed therebetween to facilitate feeding said sheets in substantially flat form throughout said device.

8. The sheet rolling device defined in claim 6, in which said upper support member is pivotable through at least three predetermined positions for positioning said upper guide fingers, to guide said sheets to roll them up with

face curls, to guide said sheets to roll them up with back curls and to permit feeding said sheets substantially flat, said lower support member is pivotable through at least two predetermined positions for positioning said lower guide fingers, to guide said sheets to roll them up with face or back curls and to permit feeding said sheets substantially flat, locking means are provided associated with the upper support member for holding said upper support member in at least said three predetermined positions, and limit means are provided associated with the lower support member for restricting the pivotal movement of said lower support member between at least said two predetermined positions.

9. A sheet rolling device for rolling a sheet having a face curl to produce a roll in which the sheet has a face curl and for rolling a sheet having a back curl to produce a roll in which the sheet has a back curl, comprising, in combination, feed means for advancing a sheet endwise in one direction, a pivotably mounted upper support, a plurality of spaced apart upper guide fingers, each of which is fixedly mounted at one end on said upper support, a plurality of finger extensions, each of which is pivotably connected to one of the upper guide fingers at the end of the guide finger remote from said upper support, a pivotably mounted lower support, a plurality of spaced apart lower guide fingers, each of which is fixedly mounted at its end on said lower support and has a concave guiding surface for guiding said sheet as it is rolled, and a feed roller positioned adjacent said lower support, said feed roller being rotatable in one direction for forming a roll with the rolled-up sheet having a face curl and being rotatable in the opposite direction for forming a roll with the rolled-up sheet having a back curl.

10. A sheet rolling device for rolling sheets having face curls to provide rolls in which the sheets have face curls, for rolling sheets having back curls to provide rolls in which the sheets have back curls, and for delivering uncurled sheets substantially flat, comprising, in combination, an upper assembly, an upper feed roller positioned adjacent said upper assembly, and a lower assembly; said upper assembly comprising a pair of spaced supporting arms, a cooperating roller rotatably mounted at each of its ends on one of said supporting arms and engaged with

and driven by said upper feed roller, a mounting tube pivotably mounted at its ends on said supporting arms adjacent said cooperating roller, a plurality of spaced apart upper guide fingers fixedly mounted at their ends on said mounting tube, a plurality of arcuate shaped finger extensions, each of which is pivotably connected to one of said upper guide fingers at the end of the guide finger remote from said mounting tube, and a setting block secured to one end of said mounting tube adjacent one of said supporting arms for locking said mounting tube in one position relative to said arms in which said upper guide fingers are positioned for guiding said sheets having face curls to roll them up with a face curl, in another position in which said upper guide fingers are positioned for guiding said sheets having back curls to roll them up with a back curl and in a third position in which said upper guide fingers permit substantially flat feeding of said uncurled sheets; and said lower assembly comprising a pivotably mounted lower supporting member having its axis parallel to the axis of said mounting tube, a plurality of spaced apart lower guide fingers fixedly mounted on said lower supporting member, each of which has a concave guiding surface, a pair of stops associated with said lower supporting member for restricting the pivotal movement thereof between two pre-determined positions in one of which said concave guiding surfaces are positioned for guiding said sheets as they are rolled, and a lower feed roller positioned adjacent and parallel to said lower supporting member, said lower feed roller being rotatable in one direction for forming a roll with the rolled-up sheet having a face curl and being rotatable in the opposite direction for forming a roll with the rolled-up sheet having a back curl.
